UNITED STATES PATENT OFFICE.

FRANK EATOCK RYDER, OF BOLTON, ENGLAND.

VERTICAL AUTOMATIC TURNING AND LIKE MACHINE TOOL.

Application filed November 3, 1924. Serial No. 747,639.

To all whom it may concern:

Be it known that I, FRANK EATOCK RYDER, a British subject, residing at Turner Bridge Works, Bolton, in the county of Lancaster, England, have invented certain new and useful Improvements Relating to Vertical Automatic Turning and like Machine Tools, of which the following is a specification.

This invention relates to vertical automatic turning and like machine tools of the type comprising a plurality of chucks, or work holding and rotating spindles, mounted upon a rotatable bed adapted to bring the said chucks or spindles in due order into 10 the correct positions for enabling the series of tools or cutters to operate upon the work.

The invention has for its object, the construction of a machine of the said type in a compact form and such that a great variety 20 of operations may conveniently be performed upon the work with great economy and expedition.

Referring to the four accompanying sheets of explanatory drawings:—

Figures 1 and 2 show the general arrangement of a machine constructed in accordance with this invention, Figure 1 being an elevation, and Figure 2 a plan with part in section.

Figures 3 to 9 are views of various parts or details of the machine. Figure 3 is a sectional elevation, and Figure 4 a sectional plan showing means for reciprocating the tool carrying slides and also other elements 35 of the machine to be hereinafter referred to. Figure 5 is a sectional end view showing the arrangement of two gear trains of the machine and the clutch controlling the operation of the same. Figure 6 is a sectional elevation illustrating a portion of the rotating table or bed with the mechanism for effecting the rotation. Figure 7 is a sectional side elevation, and Figures 8 and 9 sectional end elevations illustrating the bed or table positioning device and other details 45 hereinafter referred to.

As illustrated in the drawings, the rotatable bed or table *a* of the machine has a conical journal or like surface *b* on its underside which is supported by a correspondingly coned bearing surface forming part of the base *c* of the machine. The said bed *a* has a central eye or aperture through which is inserted the central column *d* which supports a headstock or holder suitable for carrying vertically disposed boring, screw-

ing and other tools. Such a headstock or tool holder is represented in outline at *d'* Figures 1 and 5, but it may be of any other convenient form with its mechanism arranged in any known manner.

The said rotatable bed *a* is fitted with a series of spindles as *e* each carrying a work chuck as *e'*. The bed is intermittently rotated through a portion of a circle, equal to 60 the pitch or circular distance between the spindles *e*, by gearing driven from the belt pulley *f*, whilst the spindles *e* are rotated periodically by gearing driven from the belt pulley *g*. With the pulley *f*, which is fixed 65 on the shaft or spindle *h* there are associated two gear trains, comprising worm *i* and bevel pinion *j* both fixed to said spindle *h*. The worm *i* engages worm wheel *k* loosely mounted upon and in one way clutch 70 connection with the boss *l* which is keyed to counter shaft *m*. The bevel pinion *j* engages bevel *n* which rotates spur wheel *o*; the latter drives wheel *p* through idler *q*. The said wheel *p* is free on aforesaid counter 75 shaft *m* and is adapted for engagement by clutch member *r* feather keyed or splined to *m*. The said counter shaft *m* has keyed thereon the worm *s* for engaging worm wheel *t* forming part of cam drum *u* which is 80 keyed to shaft *v*. In the view of the said cam drum shown at Figure 7 the worm wheel *t* is omitted.

The intermittent drive to the bed or table *a* through the clutch member *r* aforesaid is 85 controlled by the said cam drum *u*. The said drum by means of its end or face cam *w* imparts longitudinal movements to a rack *x* which rotates a pinion *y* mounted on and connected by one-way spring clutch *z* (Figure 6) with the vertical shaft *1* which rotates the bed *a* through spur pinion *2* meshing with toothed annulus *3* affixed to said bed. The said cam *w* operates in association with the clock spring *4* (Figure 6) on 90 the vertical shaft *1*, the cam moving the rack *x* in the one direction to give the required rotation of shaft *1*, whilst the clock spring *4* returns the rack *x* without rotation of *1*. The sliding movements of the clutch or 95 clutch member *r* to put the said intermittent drive for the bed or table in and out of action, are imparted through lever *5* actuated by spring *6* and end projection *7* from the cam drum *u*; the said projection *7* is adapted to engage the lateral extension *8* of the said lever *5*. At Figure 5 the said 100

projection 7 is on the point of engagement with 8 to push back the latter and so withdraw the clutch member *r* from engagement with the aforesaid wheel *p* through 5 which the rotary movement is imparted to the bed or table *a*. When it is thus pushed back, against the action of spring 6, to the disengaging position the extension 8 (and thus also the lever 5) is held there by the 10 abutment of a shoulder on spring trip lever 9 with the lug 10 on the said extension. No further rotary movement will then be imparted to the table until, by a slow rotary movement of the cam drum *u* obtained 15 through the aforesaid worm driven boss *l*, the projection 7 has been moved sufficiently to trip the said lever 9 against its spring action to permit the clutch *r* to be again engaged with the wheel *p* by spring 6 acting 20 on lever 5. Another quick rotary or angular movement is then imparted to the bed or table until the clutch is again disconnected as aforesaid when the slow movement follows.

25 For the rotation of the chucks *e'* with spindles *e* there is preferably employed a change speed gear of any suitable type in association with the aforesaid belt pulley *g*, actuating a worm 11 engaging a worm wheel, 30 or annulus 12, mounted in the base of the machine and carrying with it the annulus 13 which engages the pinions 14 on the respective chuck spindles *e*.

Upon opposite sides of the rotatable bed 35 or table *a* and in radial alignment therewith, are disposed tool carrying slides as 15 supported independently of the aforesaid central column or standard *d* and preferably by means of supplementary frames as 16 40 standing on the same floor level as that of the main frame or base *c* of the machine. Each of the said slides 15 is reciprocated by a lever 17 which is rocked or oscillated by a pair of cams 18 fixed on the periphery of a 45 cam drum secured to aforesaid shaft *v*. The aforesaid cam drum *u* may carry the cams 18 for the operation of one of the slides 15 whilst for the operation of the other slide, cams 18 are mounted on a drum as *u'* fixed to 50 the opposite end of shaft *v*. By the tools carried in said slides, forming, surfacing or like operations can be readily performed on the work pieces at the stop or rest positions of the bed *a* between its intermittent rotary 55 movements, and simultaneously with the operation on the said work pieces of the tools carried by the headstock or holder *d'* on the column *d* aforesaid. Each slide 15 is preferably adapted to accommodate a plurality of 60 tools so that the work pieces at two different positions on the bed or table, or in two of the chucks *e'*, may be operated upon simultaneously from the one slide. Thus with the two 65 slides (and the invention is not limited to that number), the forming, surfacing or like

tools will be operating simultaneously on the work carried by four of the chucks *e'* on their spindles *e*.

To obtain a positive drive of the work carrying or chuck spindles *e* with smooth or 70 shockless starting and stopping of the same, at the loading and unloading position (where the work is attached to and removed from the chucks), there is arranged in association with the toothed wheel or pinion 14 of each 75 spindle, a clutch device comprising sleeves as 19 and 20 (Figure 6) disposed respectively within and without each other, each sleeve being positioned by its own spring as 21 and 22 respectively. The inner sleeve 19 is adapted to make preliminary or frictional contact between the pinion 14 and the spindle *e* and thereby enable the latter to be rotated sufficiently to ensure a smooth and shockless 80 full or positive engagement between the outer sleeve 20 and the wheel 14 by way of the claw-like or positively engaging elements at the lower end of said sleeve. The outer sleeve 20 is feather keyed or splined to the inner sleeve 19 and the latter to the spindle 85 *e*. In the example illustrated the loading and unloading position for the chucks is at A (Figure 4). At such position there is formed or attached to the base *c* of the machine beneath the bed *a*, a pair of fixed cams 90 or projections as 23 and 24 with which engage the flange on outer sleeve 20 as each spindle in turn, by the rotary angular movements of the table, approaches the said position A. On such engagement the said sleeve 20 is raised to first de-clutch it from the pinion 14 and then, on its abutment against the flange or collar at the top of sleeve 19, to de-clutch the latter from 14. The rotation of the chuck is thus arrested. 100 On the subsequent movement of the bed or table the said sleeves are carried away from the said cams 23 and 24 thus permitting the sleeves to be again clutched with the pinion 14, the clutching being first effected by the 105 frictional contact of the sleeve 19 with the said wheel followed by the positive clutching as aforesaid between sleeve 20 and the said wheel.

A ball thrust bearing collar as 25 is 110 mounted at the lower end of each spindle *e* to receive the end thrusts set up by the springs 21 and 22 aforesaid.

For the accurate positioning or indexing 115 of the bed or table *a* to bring the work chucks *e'* and their spindles *e* into correct alignment with the tools, a tapered plug or like member 26 actuated through lever 27 and spring 28 is adapted to wedge or enter 120 gaps provided in a pair of bush like parts as 29 and 30 (Figure 7) of which one is fitted in the moving bed or table *a* and the other in the fixed support *c*. The said wedge like plug or connection effectually avoids 125 any inaccuracy such as may arise with the 130

use of the ordinary positioning or indexing pins. The plug is actuated, against the spring 28, by the cam 31 on the aforesaid cam drum *u*, said cam 31 engaging the lever 5 27 as shown at Figure 7.

The aforesaid shaft *v* carrying the cam drum *u* driven from the belt pulley *f* through the gearing aforesaid, extends across the machine. At or near its centre 10 the said shaft *v* is fitted with a bevel wheel or pinion 32 engaging a like pinion 33 attached to the lower end of the vertical shaft or spindle 34 disposed in the central column or standard *d* for feeding or actuating the 15 tool slides of the head stock or holder *d'* mounted on the column. At the end of the shaft *v* opposite to that on which is secured the main cam drum *u* there is affixed a corresponding cam drum for actuating the 20 radially disposed tool slide 15 at that side of the central column. Thus, all the feed motions, both for the radially disposed tool slides 15 and the tool slides of the head- stock or holder *d'* on the central column or 25 standard *d*, are obtained from the one horizontally disposed shaft *v* which is under clutch control as aforesaid. During the slow rotary or angular movements of the shaft *v*, or when it is driven through the 30 worm *i*, the various tool slides will receive their forward or feed movements, whilst during the quick rotary movements of said shaft *v*, or when it is driven through the bevel pinion *j*, the said slides will receive 35 their quick return movements.

In the use of a machine as aforesaid the operative or attendant has simply to insert a work piece in each of the chucks *e'* when, by the intermittent rotary movements of 40 the bed *a*, they are brought to the aforesaid loading and unloading position A (Figure 4), the work pieces being removed from the chucks at the same position after they have been carried by the bed *a* through one complete rotation of the latter and subjected to the action of the respective tools during the stops between the said intermittent rotary movements of the bed *a*. Thus, after the 45 first complete rotation of the bed the operative, on the arrival of each chuck at the stop position A, removes the work piece which has been completed by the tools and inserts another piece to be similarly operated upon by the tools at the respective stop positions in the further rotation of the bed.

Having thus described my invention what I claim as new and desire to secure by Letters Patent is:—

1. In vertical automatic machine tools, the combination comprising a bed, a base on which said bed is rotatably mounted, a plurality of rotatable chucks attached to spindles rotatably mounted on the said bed, means comprising frictional and positive

clutch members giving a positive drive to 65 the spindles with shockless starting and stopping of the same, a column projecting from said base and passing centrally through the bed, a tool holder mounted on said column above the bed and the said 70 chucks thereon, means for imparting intermittent rotary movements to the bed, a plurality of supplementary bases radially disposed beyond the periphery of the bed and with the said column at the central position 75 between them, tool slides mounted on said supplementary bases and means for reciprocating the said slides, as set forth.

2. In vertical automatic machine tools having a rotatable bed and a plurality of 80 chucks attached to spindles rotatably mounted on said bed, the combination with each of said spindles of a toothed wheel, a pair of sliding sleeves splined to each other and to the spindle, a frictional clutch connection 85 between one of the said sleeves and the said wheel and a positive clutch connection between the other sleeve and said wheel, and means for putting the said clutches in and 90 out of service, as set forth.

3. In vertical automatic machine tools having the combination claimed in claim 1, means for effecting the reciprocation of the 95 said radially disposed tool slides independently of the said central column and the tool holder thereon, said means consisting of a rotating shaft extending beneath the said intermittently moving bed and the said slides, cams rotating with said shaft, and levers engaging the slides and the said cams, 100 as set forth.

4. In vertical automatic machine tools having the combination claimed in claim 1, means for effecting the reciprocation of the 105 said radially disposed tool slides independently of the said central column and the tool holder thereon, said means consisting of a shaft extending beneath the said intermittently moving bed and the said slides, driving gear for rotating said shaft, said gear including a plurality of wheel trains and clutches controlling the operative connection of said trains with the shaft, cams rotating with said shaft and levers engaging 110 the slides and the said cams, as set forth.

5. In vertical automatic machine tools having the combination claimed in claim 1, means for accurately positioning and locking the said bed after each rotary movement, comprising a tapered plug, a cam for 120 actuating said plug, and a pair of adjustable bushes forming a ring and detachably engaged by said plug, one of said bushes fitting in the bed and the other in the said base on which the said bed is rotatably mounted. 125

In testimony whereof I have signed my name to this specification.

FRANK EATOCK RYDER.
